INTERNAL COMBUSTION ENGINE

Application filed August 13, 1927. Serial No. 212,763.

This invention relates to internal combustion engines, particularly those of the four cycle type, and has for its object the provision of an engine having a novel valve means for controlling the inlet of mixture and the exhaust of burnt gases, an important feature being the elimination of the usual poppet or tappet valves.

An important object of the invention is 10 the provision of an engine of this character which on account of having an improved valve mechanism will be very quiet in operation, the particular valve mechanism employed being of the piston type, and acting to 15 force the explosive mixture into the successive cylinders in their firing order, no time being lost on any of the strokes and there being no delay in the admission of the explosive mixture.

20 A further object is to provide an engine of this character which on account of the elimination of the usual type of poppet valves will be not only quiet in operation but will be also practically free from carbon troubles 25 inasmuch as any accumulation of carbon on any of the moving parts will not in any way affect the operation of the valves, the valves being furthermore of such type that they do not need to be ground at any time as in the 30 case with those of the usual pattern.

Yet another object is to provide an engine 35 of this character in which the piston valves are positively driven by the crank shaft, it being moreover a feature that the relation 40 may be varied in order to advance or retard the action as may be desired, depending upon the nature of the work the engine is called upon to do.

An additional object is to provide an engine 45 of this character which will be comparatively simple and inexpensive to manufacture, easy to assemble, use and operate, positive in action, efficient and durable in service, and a general improvement in the art.

With the above and other objects and advantages in view, the invention preferably 50 consists in the arrangement and combination of parts and the detailed structure to be hereinafter more fully described and claimed,

and illustrated in the accompanying drawings, in which:—

Figure 1 is a vertical sectional view taken 55 through one cylinder, and illustrating the valve for controlling the inlet of fuel mixture.

Figure 2 is a similar view but the section being taken through the valve for controlling the exhaust.

Figure 3 is a sectional view taken on substantially 60 the line 3—3 of Figure 1 looking in the direction of the arrow, and

Figure 4 is a horizontal cross sectional view taken on substantially the line 4—4 of Figure 1.

Referring more particularly to the drawings, I have shown the engine as comprising the usual or any preferred crank case 10 upon which may be mounted in any desired manner any suitable number of cylinders 11 70 preferably water-jacketed indicated at 12, as is the common practice. The cylinders may be cast en bloc and are closed by means of a detachable cylinder head 13 having a suitable opening at each cylinder within which 75 is located a spark plug 14 to which a high tension current is supplied by any suitable means. Operating within the cylinder 11 is a piston 15 having a wrist pin connection 16 with a connecting rod 17 which is in turn 80 connected with the crank portion 18 of the crank shaft 19 which is journaled in any suitable manner longitudinally of the crank case 10, the crank case being preferably formed of separable sections as is a common 85 practice in order that access may be had to the crank shaft and connecting rod bearings in case of any necessity for repairing the same. Up to this point there is nothing 90 novel about the construction but all of these parts must be shown and described for the sake of clearness.

In carrying out the invention, I provide a housing 20 at one side of the crank case and cylinder, this housing being closed by a preferably removable cover plate 21 held in place 95 by any suitable means whatsoever. Journaled within this housing 20 is a crank shaft 22 having a crank portion 23 adapted to be driven by the crank shaft 19 in any suitable 100

manner as for example by means of what is called a silent chain 24 trained about sprockets 25 and 26 on the crank shafts 19 and 22 respectively. The ratio of these sprockets is such that for every two rotations or revolutions of the crank shaft 19, the crank shaft 22 will be given one rotation. The numerals 27 and 28 designate two separate cylinders which are preferably formed integrally with the cylinder block and crank case, though it is conceivable that they may be constructed separately and then attached by some suitable means. The cylinder 27 is connected with the intake manifold 29 while the cylinder 28 is connected with the exhaust manifold 30, the former being connected with any suitable carburetor, not shown, and the latter being connected, probably, with a suitable muffler, likewise not shown. The manner in which these intake and exhaust manifolds are connected with the cylinders 27 and 28 is immaterial as it forms no essential part of the invention. Operating within the respective cylinders 27 and 28 are pistons 31 and 32 having the usual wrist pin connections with connecting rods 33 and 34 respectively, in turn pivotally connected with the crank portion 23 of the shaft 22. These cylinders 27 and 28 communicate with the cylinder 11 through ports 35 and 36 which are bridged by guide elements 37 provided for the purpose of preventing touching or hanging of the packing rings 38 on the piston.

In the operation, it will be seen that at nearly the end of the power stroke, as shown in Figure 1, the piston 13 is near its lowermost position while the pistons 31 and 32 are still closing the ports 35 and 36. When the piston has completed its power stroke in the engine cylinder, it is of course necessary that the exhaust valve or piston 32 must uncover the port 36 so that as the piston 15 moves upwardly on its scavenging stroke the burnt gases will be expelled and will pass out into the exhaust manifold 30 in advance of the piston 32 which consequently acts somewhat as a pump for positively forcing this exhaust matter out. After the piston 15 has thus completed its scavenging stroke and starts back down on the intake stroke, the intake control valve or piston 31 uncovers the port 35 so that the downward movement of the pistons 15 will act to suck in a fresh charge of combustible mixture. After reaching the lower end of its intake stroke, the cylinder 15 starts upward on its compression stroke and at this time the piston 31 must of course reclose the port 35 so that the combustible mixture will be compressed in the explosion chamber. When the spark occurs at the spark plug and ignition of the charge results the piston 15 is of course forced downwardly on its power stroke. This completes the cycle of operation. It will of

course be apparent that after the piston 31 has moved downwardly to permit the explosive mixture to enter the cylinder 11 and starts upwardly the explosive mixture formerly behind the piston 31 becomes compressed and is therefore forced positively back into the intake manifold and is applied under pressure to the next cylinder in the proper firing order. In view of this action, it is apparent that there will be a positive feed of combustible mixture to the successive cylinders and the action will be consequently accelerated to a material degree.

From the foregoing description and a study of the drawings, it will be apparent that I have thus provided a simply constructed, inexpensive and highly efficient internal combustion engine which does not in any way make use of the usual and well known poppet or tappet valve and which will therefore be practically noiseless in operation, in so far as valve movement is concerned, and free from carbon troubles. If for any reason, it should be found necessary to retime the parts to accelerate or retard the action, it is apparent that after the noiseless chain 24 is disconnected, the pistons 31 and 32 and 15 may be moved relatively, subsequently to which the chain 24 may be reengaged with the sprockets 25 and 26 in a manner to be well understood. It is for this reason that the plate 21 is preferably detachable so as to give access to the interior of the housing 20. It is really believed, that from the foregoing, the construction, operation and advantages will be readily apparent to one skilled in the art without further explanation.

While I have shown and described the preferred embodiment of the invention, it should be understood that I reserve the right to make all such changes in the details of construction and the arrangement and combination of parts as will not depart from the spirit of the invention or the scope of the subjoined claim.

Having thus described the invention, I claim:

An internal combustion engine comprising a cylinder having inlet and exhaust ports of the same transverse sectional area and communicating with the cylinder at the same level, a piston slidable in said cylinder, a crank shaft journaled beyond the end of the cylinder, a rod connecting said piston with the crank shaft, a second crank shaft journaled at the side of the first mentioned crank shaft and having crank arms disposed approximately ninety degrees apart, means operatively connecting the first mentioned crank shaft with the second mentioned crank shaft and ratioed to effect one revolution of the second mentioned crank shaft incident to two revolutions of the first mentioned crank shaft, a pair of cylinders connected with said

ports respectively, a piston slideable in each of the last mentioned cylinders, said pistons having at their upper flat ends surfaces lying in planes at right angles to the vertical axes of the pistons, a rod connecting each of the last mentioned pistons at its center with one of the arms of the second mentioned crank shaft, said arms being of such length as to draw the said flat surfaces of the pistons to the level of the surfaces of the lower walls of the ports as the arms pass under the shaft, whereby said cylinders and pistons act as suction and compression pumps at the intake and exhaust ports respectively.

15 In testimony whereof I affix my signature.
JOHN ALEXANDER McMILLAN.
